CAR DOORLOCK

Wilfred A. Beauchamp, Chicago, Ill., assignor to
 Camel Company, Chicago, Ill., a corporation of
 Illinois

Application June 13, 1932, Serial No. 616,873

12 Claims. (Cl. 292—283)

This invention relates to car door locks and is directed more particularly to locks for sliding car doors.

It is an object of this invention to provide a lock for sliding car doors embodying a lock member and a locking pin only insertable in said lock member prior to the securement thereof to a car and not normally removable therefrom after such securement.

10 A further object is to provide a lock for sliding car doors embodying a hasp and a tapered fastening pin cooperating with said hasp to secure said doors in closed position.

A further object is to provide a lock for sliding car doors embodying a downwardly tapering fastening pin and means for preventing undesired upward creeping of said pin in the operative position of said lock.

20 A further object is to provide a lock for sliding doors comprising a member carrying a vertically movable fastening pin, said member and said pin being provided with cooperating projections for preventing upward creeping of said pin in the operative position of said lock beyond a predetermined point.

25 A further object is to provide a lock for sliding car doors comprising a vertically positioned fastening pin having an inclined side and a hasp having a laterally extending similarly inclined lug engageable with the inclined side of said pin in the operative position of said lock.

30 A further object is to provide a lock for sliding doors comprising a vertically positioned fastening pin having a side forming an obtuse angle with the face of said pin and a hasp having a similarly inclined lug engageable with said side of the pin in the operative position of said lock.

35 A further object is to provide a lock for sliding car doors comprising a member, a tapered pin and a hasp, the pin and the member having projections engageable when the pin is in a substantially vertical plane to prevent upward movement thereof, and said member, pin and hasp having cooperating means for maintaining said pin in a substantially vertical plane.

40 A further object is to provide a lock for sliding doors comprising a member and a fastening pin, said member and pin having cooperating projections engageable in the elevated and forwardly inclined position of the pin for support of the pin in its elevated position.

45 Other objects of this invention will become apparent as the description thereof proceeds.

In the drawings forming a part of this specification

50 Figure 1 is a fragmentary elevation showing the application of the lock of the invention to the double doors of a railway house car.

55 Figure 2 is a view similar to Figure 1 showing the double doors and the lock in two of their po-

sitions to indicate the mode of operation of the lock.

Figure 3 is a horizontal section taken on line 3—3 of Figure 1.

Figure 4 is a vertical section taken on line 4—4 65 of Figure 1.

Figure 5 is a vertical section taken on line 5—5 of Figure 4.

Figure 6 is a sectional view similar to Figure 4 illustrating the manner of supporting the fastening pin upon the lock member in the inoperative position of the pin.

Figure 7 is a horizontal section taken on line 7—7 of Figure 1.

This invention embodies improvements in the 75 invention described and claimed in the co-pending application filed October 11, 1930, Serial No. 487,939 now Patent No. 1,877,263, granted Sept. 13, 1932.

80 As in the above identified co-pending application the improved lock for car doors of the instant invention is shown applied to the double doors of an automobile house car. The invention, however, is of sufficient scope to permit the application of the improved lock upon box cars— 85

that is, upon cars in which single sliding doors are employed upon each side of the car. The doors illustrated are the auxiliary door 10 and the main door 11 of the double door construction.

The auxiliary door, as clearly illustrated in Figures 1, 2 and 3, is preferably made of metal embodying a metallic panel 12 provided with a plurality of spaced horizontal corrugations 13 and a vertical corrugation 14 adjacent each vertical margin of the door. Only one of the vertical corrugations is illustrated. Secured to the forward 90

edge of the auxiliary door 10 is a metallic post or jamb 15 provided with a nailing strip 16 and maintained against rotation relative to said door by means of a knee brace 17 secured to the post 100

and to the door. Riveted to the post 15 through a flange positioned between said post and the margin of the forward edge of the auxiliary door is an angle member 18 which cooperates with the post to provide a recess 19 to receive the 105

front edge angle member 20 secured to the forward margin of the main door 11. The vertical corrugation 14 is preferably reinforced by means of the channel shaped member 21. The main door 11 is also of metallic construction and embodies a metallic panel 22 provided with a plurality of horizontal corrugations 23 and a plurality of vertical corrugations 24 disposed, 110

respectively, adjacent the vertical margins of the door. One only of such vertical corrugations is 115 illustrated.

The lock for the doors above described comprises a hasp fastener 25 positioned upon one of the horizontal corrugations 23 of the main door 11 and secured thereto by means of rivets 26 ex- 120

tending through said fastener, the panel 22 and a backing member 27 positioned on the inner side of the door. As clearly illustrated in Figure 3 of the drawings the backing member which lies within the horizontal corrugation 23 to which the hasp fastener is secured is extended so as to lie within the vertical corrugation 24. This extension of the backing member 27 is permitted because of the fact that the horizontal corrugations merge within the vertical corrugations of the door. By such extension the neck 28 of the hasp fastener is adapted to extend through aligned openings in the corrugation 24 and in the backing member 27 so that the stress applied to said neck is carried directly back through the backing member to the securing rivets 26. The extension additionally serves to reinforce the vertical corrugation 24 and because of the integral structure between the reinforcing portion of the backing member and the remainder of said member said portions is effective to prevent tearing of the panel at the vertical corrugation and the pulling out of the end of the neck portion 28 extending into said portion. The subject matter of the hasp fastener as above described is not claimed herein but will be made the subject matter of a separate application.

Pivotedly supported from the neck of the hasp fastener is a hasp 29. The hasp is provided with a slot 30 and extending from said hasp adjacent one end of said slot is a vertically inclined lug 31. Attention is invited to the fact that the lug 31 is provided with a face or abutment portion 32 extending at an obtuse angle from the outer face of the hasp.

A lock member 33 is secured to the auxiliary door 10 by means of rivets 34 extending through said member, the door and a backing member 35. The lock member is positioned upon a horizontal corrugation 13 of the auxiliary door and the backing member 35 lies within said corrugation. Additional rivets 36 are used to secure the lock member to the door. The lock member 33 is provided with a pair of vertically spaced housing members 37 and 38. A lug 39 extends from the lock member between the housing members. The housing member 37 is provided with an inward extension 40 positioned opposite to a downwardly and outwardly inclined portion 41 provided on the rear of the housing member. As clearly shown in Figure 7 of the drawings this downwardly and outwardly inclined portion of the housing member extends from the right hand portion of the housing member as viewed in Figure 7, stopping substantially midway between the ends of said housing member. The remainder of the rear of the housing member presents a substantially vertical wall. The lower housing member 38 is provided with a lug 42 extending downwardly therefrom. The outer end of the lower housing member is extended to provide a flange 43 in which a slot 44 is provided. A shoulder 45 extends outwardly from the lock member adjacent said flange 43 in position to underlie the fastening pin 46 of the door lock when said pin is in a predetermined position.

The fastening pin 46 is provided preferably with a straight side 47 adapted to abut against straight sides of the housing members 37 and 38 and an inclined side 48, the inclination of which corresponds to the inclination of the lug 31 provided on the hasp. The fastening pin is adapted to be received within the housing members 37 and 38 and to have vertical movement relative thereto. The inclined side of the outer

face of the fastening pin extends at an obtuse angle from said pin as indicated at 49 and corresponds to the obtuse angle on the face 32 of the lug 31 of the hasp. The lower end of the fastening pin is provided with a lateral projection 50 in which an opening 51 is formed. Spaced vertically above the lateral projection is a shoulder 52. A head 53 is provided upon the fastening pin.

With a door lock of the character above described the fastening pin 46 must be assembled with the lock member 33 by insertion of the pin into the housing member prior to the securement of said lock member to the auxiliary door or other part of the car. This assembly is effected by inclining the pin rearwardly relative to the lock member so that the lateral projection 50 at the lower end of the pin may be slid along the downwardly and outwardly inclined portion 41 at the rear of the upper housing member. After the assembly of the pin with the lock member and the attachment of said member to the auxiliary door it is impossible to completely release the pin from the lock member inasmuch as engagement between the lateral projection 50 and the shoulder 40 provided on the upper housing member prevents such retraction when the pin is in a vertical plane. The fastening pin cannot be inclined rearwardly, because of its engagement with the auxiliary door, a sufficient amount to permit the pin to be withdrawn along the downwardly and outwardly inclined portion of the upper housing member. As clearly illustrated in Figure 6 of the drawings, the pin in its inoperative position may be inclined forwardly so that the lower portion thereof engages the rear of the upper housing member and the shoulder 52 rests upon the inward extension 40. In view of this construction, it is not necessary for the operator to maintain the pin in retracted position while releasing or applying the hasp in proper relation with the lock member.

In positioning the hasp relative to the lock member prior to the projection of the pin in locking position the lug 39 of the lock member must be seated within the slot 30, provided in the hasp, in order that the fastening pin may be properly seated. This insures the projection of the pin in its locking position to such an extent that alignment between the slot 51, provided in the pin, and the slot 44, provided in the flange of the lock member, will be had so that a seal (not shown) may be extended through said aligned slots.

A certain amount of difficulty has been experienced with the lock of the hereinbefore identified co-pending application with regard to the tendency of the tapered pin to creep upwardly to such an extent that the seal has, in a few instances, been broken. The construction of the door lock of the instant application obviates this difficulty. It will be apparent from a casual inspection of Figure 4 of the drawings that when the fastening pin 46 is maintained in a substantially vertical plane, engagement between the lateral projection 50, adjacent the lower end of the pin, and the lug 42, provided on the lower housing member 38, will occur prior to the breaking of the seal and prevent further upward movement of the pin. The shoulder 45 extending from the lock member and underlying the pin, aids in maintaining the position of the pin in a substantially vertical plane. However, in order not to interfere with the projection of the pin within the housing members and to permit release thereof, the coaction above described between the lateral extension 50 and the lug 42 may not be had 150

if the pin assumes such position within the housing members that the lower edge thereof is positioned slightly above the shoulder 45. To provide against this contingency the obtuse angularity 5 between the face 32 of the lug 31 of the hasp and of the tapered side of the fastening pin 46 is provided. It is clear, with such obtuse angularity of these parts, that there will be a 10 tendency to maintain the pin in a substantially vertical plane under the pull exerted upon the hasp when in its operative position. The possibility of upward creeping of the pin has been further minimized by the vertical inclination given to the lug 31 of the hasp and the side of the pin 15 cooperating with said lug. As clearly illustrated in Figure 5 of the drawings the straight side of the pin abuts against straight sides of the housing members 37 and 38 in the operative position of the pin. This relationship between the pin, the 20 hasp and the housing members has been found, through actual experimentation, to most effectively resist upward movement of the pin.

The structural embodiment of the invention may be subjected to many modifications and 25 changes in the details thereof without departing from the spirit of the invention. It is intended, therefore, that all such modifications and changes shall be comprehended within the invention, which is to be limited only by the scope 30 of the claims appended hereto.

I claim:

1. A lock for a sliding car door comprising a lock member adapted to be secured to a relatively stationary part of the car, a hasp fastener secured to said door, a hasp carried by said fastener, a vertically movable tapered fastening pin carried by said member, a lug provided on said member, said pin having a projection engageable with said lug in the operative position of said lock to prevent 40 upward creeping of said pin beyond a predetermined point.

2. In a railway house car having a sliding door, a lock for said door, said lock comprising a lock member adapted to be secured to a relatively stationary part of said car, a hasp carried by said, 45 said member having a vertically movable tapered fastening pin and a lug, a projection provided on said pin adjacent the lower end thereof, said hasp in the operative position of said lock having engagement with said member and underlying said pin, said projection being engageable with said lug to prevent upward movement of said pin and disengagement from said hasp.

3. In a railway car having a movable member and a relatively stationary member, a lock for 50 said movable member comprising a lock member provided with a lug adapted to be secured to one of said car members, a hasp adapted to be secured to the other of said car members, a vertically movable tapered fastening pin carried by said lock member, a projection provided on said pin, said projection being engageable with said lug in the operative position of said lock to prevent upward movement of said pin, and means to establish said engagement.

4. In a railway car having a movable member and a relatively stationary member, a lock for 55 said movable member comprising a lock member provided with a lug adapted to be secured to one of said car members, a hasp adapted to be secured to the other of said car members, a vertically movable tapered fastening pin carried by said lock member, a projection provided on said pin, said projection being engageable with said lug in 60 the operative position of said lock when said pin

lies in a substantially vertical plane, and means to position said pin in said plane.

5. In a railway car having a movable member and a relatively stationary member, a lock for 65 said movable member comprising a lock member provided with a lug adapted to be secured to one of said car members, a hasp adapted to be secured to the other of said car members, a vertically movable tapered fastening pin carried by 70 said lock member, a projection provided on said pin, said projection being engageable with said lug in the operative position of said lock, said lock member having a shoulder extending between said lock member and the inner face of said pin for a portion of the upward movement of the 75 pin to establish said engagement.

6. In a railway house car having a sliding door, a lock for said door, said lock comprising a lock member adapted to be secured to a relatively stationary part of said car, a hasp carried by said door, and a vertically movable tapered fastening pin carried by said lock member, said pin having one vertical side and one inclined side, said hasp being provided with a laterally extending lug similarly inclined and engageable with the inclined 85 side of said pin in the operative position of said lock, the vertical side of said pin abutting said lock member.

7. In a railway house car having a sliding door, a lock for said door, said lock comprising a lock member adapted to be secured to a relatively stationary part of said car, a hasp carried by said door, and a vertically movable tapered fastening pin carried by said lock member, said pin having one vertical side and one inclined side, said hasp 90 being provided with a laterally extending abutment similarly inclined and engageable with the inclined side of said pin in the operative position of said lock, the vertical side of said pin abutting said lock member, said inclined side and said abutment extending, respectively, obtusely from the outer face of said pin and said hasp.

8. In a railway house car having a sliding door, a lock for said door, said lock comprising a lock member adapted to be secured to a relatively stationary part of said car provided with spaced 95 housings, a hasp carried by said door, a vertically movable tapered locking pin carried in said housings, a lug depending from the lower of said housings, said pin having a projection adjacent its lower end engageable with said lug in the 100 operative position of said pin and said hasp to prevent upward movement of said pin.

9. In a railway house car having a sliding door, a lock for said door, said lock comprising a lock member adapted to be secured to a relatively stationary part of said part, a housing provided on said lock member, a portion of the rear wall of said housing being inclined downwardly and outwardly and a locking pin, said pin being only insertable in a downwardly and outwardly inclined position in said housing at said inclined portion prior to the securement of said lock member to the relatively stationary part of the car.

10. In a railway house car having a sliding door, a lock for said door, said lock comprising a lock member adapted to be secured to a relatively stationary part of said car, a housing provided on said lock member, a portion of the rear wall of said housing being inclined downwardly and outwardly and a locking pin, said pin being only insertable in a downwardly and outwardly inclined position in said housing at said inclined portion prior to the securement of said lock member to the relatively stationary part of the car, and

means preventing removal of said pin after securing of said lock member to said part of the car.

11. In a railway house car having a sliding door, a lock for said door, said lock comprising a lock member adapted to be secured to a relatively stationary part of said car, a housing provided on said lock member, a portion of the rear wall of said housing being inclined downwardly and outwardly and a locking pin, said pin being only insertable in a downwardly and outwardly inclined position in said housing at said inclined portion prior to the securing of said lock member to the relatively stationary part of the car, and means preventing removal of said pin after securing of said lock member to said part of the car, said means comprising a lateral extension provided on said housing engageable with an op-

posed laterally extending projection provided on said pin.

12. In a railway house car having a sliding door, a lock for said door, said lock comprising a lock member adapted to be secured to a relatively stationary part of said car, a hasp carried by said door, and a vertically movable tapered fastening pin carried by said lock member, said pin having one vertical side and one inclined side, said hasp being provided with a laterally extending abutment having a similarly inclined side engageable with the inclined side of said pin in the operative position of said lock, the vertical side of said pin abutting said lock member, one of said inclined sides extending obtusely to the outer face of the part upon which it is provided.

CERTIFICATE OF CORRECTION.

Patent No. 1,950,837.

March 13, 1934.

WILFRED A. BEAUCHAMP.

It is hereby certified that error appears in the printed specification of the above numbered patent requiring correction as follows: Page 3, line 132, claim 9, for "part" second occurrence, read car; and that the said Letters Patent should be read with this correction therein that the same may conform to the record of the case in the Patent Office.

Signed and sealed this 15th day of May, A. D. 1934.

Bryan M. Battey

(Seal)

Acting Commissioner of Patents.
